[57] CLAIM

The ornamental design for a therapeutic posture chair,
as shown and described.

DESCRIPTION

FIG. 1 is a side elevational view of a therapeutic posture chair showing my design, a fragmentary human figure being shown therein in broken lines for illustrative purposes only.

FIG. 2 is a front elevational view thereof;

FIG. 3 is a left side elevational view thereof;

FIG. 4 is a rear elevational view thereof;

FIG. 5 is a top plan view thereof; and

FIG. 6 is a bottom plan view thereof.

FIG. 1

FIG. 2

FIG. 3

FIG. 4

FIG. 5

FIG. 6
